CIGARETTE CASE

Julius P. Krieger, Louisville, Ky.

Application June 14, 1932. Serial No. 617,217

2 Claims. (Cl. 206—41)

This invention relates to carrying cases or kits and has special reference to a cigarette case or kit.

One important object of the invention is to improve the general construction of devices of this character.

A second important object of the invention is to provide an improved case for this purpose having a body of rigid material and of the size and proper 10 shape to accommodate a pack of cigarettes.

A third important object of the invention is to provide an improved case for this purpose wherein the cigarettes may be carried and which will protect them from breaking or crumpling and 15 from perspiration.

A fourth important object of the invention is to provide a suitable match holder in combination with such a case.

A fifth important object of the invention is to 20 provide an improved case of this class having a hook or the like for securing the case in position on or to a waist belt, the pocket and other places, the hook being so arranged and positioned as to permit free access to the contents of the 25 case, both cigarettes and matches, when the case is supported by the hook.

A sixth important object of the invention is to 30 provide a novel case of the class having its bottom provided with a finger opening to permit ready ejection of the cigarette package from the case.

A seventh important object of the invention is to 35 provide a novel form of cigarette and match holding case having a flexible cover adapted, when closed, to cover both the cigarettes and the matches, the cover and case being provided with coacting snap button means for securing the cover in closed position.

With the above and other objects in view as 40 will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view of the case without the match holding means, the case being 50 shown as open and partly broken away to disclose the finger opening.

Figure 2 is a perspective view of the case showing the cigarettes and matches in position, the cover being broken away.

Figure 3 is a view similar to Figure 2 but

broken away to show the manner of ejecting the cigarette package.

Figure 4 is a rear perspective showing the case closed.

Figure 5 is a front perspective showing the case 60 closed.

Figure 6 is a plan view of a blank from which the case is constructed.

Figure 7 is a detail front view of a slightly modified form of the device.

Figure 8 is a vertical section through the front wall of the modified case showing a match pocket supported thereon.

Figure 9 is a detail section on the line 9—9 of Figure 6.

Figure 10 is a perspective view from the rear of a slightly modified form of case.

In the embodiment of the invention here shown the case is illustrated as being made from material such as genuine leather, imitation leather, 75 textile material, fibre, rubber, paper, wood, metal or any other suitable material. Preferably in the form here shown the case is made up of a plurality of layers of material. This case has a rectangular back 10 from the side edges of which 80 extend the side portions 11. From the bottom edge of the back extends the bottom 12 and the front wall 13 extends upwardly from the forward edge of the bottom and is provided with side flaps 14 which overlap the sides 11 and are secured thereto as by the stitching 15. From the top edge of the rear wall 10 extends a cover which consists of a top portion 16, connected directly to the said top edge, and a front portion 17 connected to the front edge of the portion 16, the 85 top portion 16 being suitably defined from the back wall and front portion 17 by fold lines 18, creased or otherwise formed in the material to permit easy bending at these places.

As shown in Figures 6 and 9, the case may be 90 made from a laminated blank having the sides, front, back and bottom layers of three layers 10' and 10'', the layers 10' forming the outer surface and lining of the case and the layer 10'' being of stiff material. For instance, the layers 10' 100 may be of thin leather and the layer 10'' of fibre board. In such case the outer layers 10' are continued at the top, beyond the fibre layer, to form the parts 16 and 17 which thus consist of but two layers of flexible material, a row of stitching 17' extending around the periphery of these parts to prevent any separation of the layers. Similarly, the top edges of the front 13 and side portions 14 are provided with stitching 13' for the same 105 purpose. The case thus formed is of proper shape 110

and size to accommodate a cigarette package C which, as may be seen from Figure 2, snugly fits the case with its open upper end flush with the top of the case body.

- 5 Across the front of the case, midway of its height, extends a strap 19 which has its ends secured to the front wall 13 by stitch lines 20 at the ends of the strap, the middle portion of the strap being thus left free from the wall 13. This 10 strap forms a match holder and, in use, the cover of an ordinary paper match packet M is slipped up behind the strap so that the latter lies between the back of the cover and the matches themselves, the striker strip being thus exposed. The 15 portion 17 of the cover is of such size as to fully cover and protect the matches when the case is closed and the cover and front wall are provided with coacting snap button parts 21 for holding the case cover securely in closed position.
- 20 As best shown in Figures 1, 3, and 5, the bottom 12 is provided with an opening 22 of proper size to admit a finger so that the packet C may be pushed up, as in Figure 3, for removal from the case as desired.
- 25 A U-shaped spring wire clip or hook 23 has a pair of offset base portions 23 at the ends of its legs and these are secured to the back wall 10 at the center of the top portion thereof so that the clip or hook may be engaged on a belt, trouser's band or other suitable place. By this particular arrangement of the hook on the back of the case the case cover is left free and convenient for opening and closing and access may be had to the cigarettes and matches without removing the 30 case from the place where it is attached.

In the form of the invention shown in Figures 7 and 8 it will be seen that the strap 19 is replaced by an integral strap 23^a formed by cutting two parallel slits 24 transversely of the front portion 13. In this form the strap is pushed out slightly when it is desired to attach the match 40 pocket.

As shown in Figure 10, the clip or hook may be omitted and in this form it is intended that the 45 device is to be carried in one's pocket.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. A blank for cigarette cases formed of a pair of layers of flexible leather-like material, said layers constituting inner and outer layers respectively and each including a rectangular back portion, rear side portions of rectangular form extending from the side edges of the back portion and of equal length thereto, bottom tabs extending from the lower edges of the rear side portion, a bottom portion of rectangular form extending from the bottom edge of the back portion and of equal width thereto, a front portion extending from the edge of the bottom portion opposite the back portion and of equal width and height to the back portion, front side portions extending from the side edges of the front portion, all of said portions and tabs having between them a middle layer of stiff material such as fibre board, each of the flexible blanks having a top portion of rectangular form extending from the top edge of the back portion and of equal width thereto, and a front flap extending from the edge of the top portion opposite the back portion and of equal width thereto, the top portions and front flaps of said blanks being in contact throughout and being stitched together at the side edges of the top and front portions and at the end of the top portion.

2. Cigarette case formed from the blank of claim 1 with the front and back portions parallel to each other and at right angles to the top, bottom and side portions and the tabs overlapping the bottom portion at the sides thereof, said front side portions at each side of the case overlapping the corresponding rear side portions and stitched thereto, the front flap overlapping the front portion, and means for detachably connecting the free end of the front flap and lower part of the front portion.
